Primary Examiner — Mimosa De(74) *Attorney, Agent, or Firm* — Suiter Swantz IP(57) **CLAIM**

The ornamental design for a pilot seat, as shown and described.

DESCRIPTION

FIG. 1 is a front perspective view showing a pilot seat;

FIG. 2 is a top plan view;

FIG. 3 is a front elevation;

FIG. 4 is a first side elevation;

FIG. 5 is a back elevation;

FIG. 6 is a second side elevation; and,

FIG. 7 is a bottom plan view.

The broken-line subject matter is included for the purpose of illustrating portions of the article of manufacture and form no part of the claimed design.
